THERMOSTATICALLY CONTROLLED
RADIATOR VALVE

Edward J. Zeitlin, Yorktown, N. Y.

Application November 12, 1947, Serial No. 785,223

8 Claims. (Cl. 236—64)

1

This invention relates to a thermostatically controlled radiator valve and more particularly to a radiator air release valve that is opened or closed by a thermostatic means controlled by room temperature.

An object of this invention is to provide a radiator air release valve that will control the opening or closing of the valve based upon the surrounding room temperature.

A still further object of this invention is to provide a radiator air release valve that is provided with a single valve means but a double control for said valve, one control effecting the closing of the valve due to the temperature of the steam entering the valve, the other control being connected to thermostatic means to open or close the valve according to room temperature.

A further object of this invention is to provide a steam radiator air control valve that is provided with a single valve means but a double control for said valve, one control effecting the closing of the valve due to the temperature of the steam entering the valve, the other control being connected to a temperature responsive element to open or close the valve to a greater or lesser degree according to the ambient temperature surrounding the temperature responsive element.

A further object of this invention is to provide a steam radiator air control valve in which the orifice area is varied inversely with the rise or drop in room temperature.

Other objects of this invention shall be apparent by reference to the accompanying detailed description and drawing in which

Figure 1 illustrates a cross sectional view of the valve,

Figure 2 illustrates a cross sectional view of another embodiment of this invention,

Figure 3 illustrates an end elevational view taken on line 3—3 of Figure 2, and

Figure 4 illustrates a partial view of a valve similar to Figure 1 and a temperature responsive element both shown partially in cross section.

Referring to Figure 1 which illustrates a cross sectional view of a valve according to this invention there is a main body 10 having a threaded end 11 for attachment to a radiator (not shown). The body 10 is in the shape of a hollow elbow member having a port 12 at one end and an open bore 14 at its other end.

An outer shell or casing 15 is secured to the body 10 by welding or otherwise. The shell forms a lip or stop 15A to limit the movement of a valve seat 16 which is slidably mounted in the bore 14, and a spring 17 is mounted between the

seat 16 and a shoulder 18 of the bore 14. Thus the seat 16 will be pressed outwardly from the shoulder 18, and limited in its outward movement by the stop 15A. A shell 20 is threadably secured to member 15 and is provided with a stop pin 21 so that when member 20 has been secured it may be turned one revolution or less for adjustment purposes. Member 20 also supports a thermostatic bellows 23 that is joined to a diaphragm 24 to thus enclose a chamber 25. The chamber 25 is filled with a liquid that is affected by changes in temperature to expand with a rise in temperature according to a prescribed range of temperatures, in this instance varying between 50° and 85°. A stem 27 with a passage 26 is also sealed to the end portion 28 of the bellows 23. The stem 27 is either a part of or affixed to a valve head 29, the valve head conforming to and mating with the valve seat 16. The passage 26 extends through the valve head 29 and is open to and connected with a fluid chamber 30. The chamber 30 and passage 26 is filled with a fluid similar to the chamber 25. It is necessary to prefill both chambers and passage and to set shell 20 in an exact relationship with the casing 15, so that casing 15 may be calibrated around its periphery 31 and thus have the valve 29 open and close according to predetermined temperature settings. The valve as illustrated in the drawing is positioned with the threaded end 11 in the uppermost position. This particular positioning was provided so that the hot air escaping as indicated by the arrows would rise and thus would not affect the outer shell of member 20 and by convection effect a true temperature response. The valve 10 may also be inverted and mounted so that the threaded end 11 would appear at the lower portion of the drawing. In operation the valve will be mounted to a radiator by means of its threaded portion 11. With chamber 30, passage 26 and chamber 25 pre-filled the valve is ready for use. When member 20 has been properly positioned according to the calibrated scale 31, the arrow 33 may be moved right or left to the temperature setting desired. When the room temperature is lower than the valve setting on scale 31 the valve will be open, thus air may escape from the radiator past valve seat 16 and out the openings 34 as shown by the arrows, until steam or vapor reaches the chamber 30. The ambient heat around chamber 30 will cause the liquid to expand and the fluid pressure will be carried through the passage 26 and exert a pressure on the bellows 23, thus the valve 29 will be pressed firmly on the seat 16. The ac-

tion of the valve in this instance is to close when steam or hot vapor contacts the chamber 30 to thus close off the flow and prevent the escape of vapor or steam. Any excessive pressure due to the expansion of the liquid in the chambers will force valve seat 16 to be pressed firmly against the spring 17; this movement of the seat provides an over-ride action. The air flow normally passing valve seat 16 when the valve is open may also be stopped by other means affecting the action of the thermostatic bellows 23, that is in the event the room temperature is above the setting of the valve according to the scale 31 then the valve 29 will be closed. The outside room temperature or ambient temperature thus affects the fluid in chamber 25 and the fluid produces a pressure on the bellows 23 thus closing the valve. It is to be noted that chamber 25 presents a large area for the action of slight variations in temperature whereas chamber 30 presents a very small area for the large variation of heat, that is, steam or vapor will normally give a rapid rise in temperature. Thus chamber 25 responds to small variations in temperature for opening or closing valve 29 whereas chamber 30 responds to the large variation in temperature caused by the contact of steam or vapor, thus a very quick response is obtained. It is to be noted that the valve functions as a normal radiator valve to cut off the escape of steam or vapor. It is to be further noted that the escape of air, if hot, past the seat 16 will pass out openings 34 and will tend to rise, thus the air flow has little or no effect on the thermostatic bellows element.

Referring to Figure 2, there is illustrated another embodiment of this invention in which there is a main valve body 40 having a threaded end 41 for attachment to a radiator (not shown). The body 40 is tubular in formation, one end having a port 42 passing through the threaded portion 41. The body 40 is provided with three different diameter bores on the opposite end to the port 42. The main portion 43 is the smallest in diameter, a portion 44 is slightly larger and a portion 45 forms the largest bore. The outer end of bore 46 may be threaded or may be welded to a tubular member 50. The member 50 at one end thereof supports a diaphragm 51 having a bellows 52 integral therewith. The bellows 52 is provided with a base 53 and a stem 54 is mounted on the base 53. The stem 54 is provided with a valve head 55 having a valve face 56 that normally abuts with a valve seat 57. The valve seat 57 is slidably mounted in the bore 44 and is resiliently retained against the valve face 56 by a spring 58, that is also mounted in the bore 44, and bears against a shoulder 59. The stem 54 extends through the valve head 55 into the bore 43 of the main body 40. There is a passage 60 through the center of the stem 54. On the end of the stem 54 in the main body 40 of the valve, there is a fluid chamber 62 that is sealed except for the passage 60 with which the chamber connects. The opposite end of passage 60 opens through the base 53 into a fluid chamber 65 that is enclosed by the diaphragm 51 and bellows 52 on one end of the member 50 and is provided with a diaphragm 66 and a bellows 67 that is positioned in an opposite relationship to the bellows 52, to close the opposed end of the chamber 65. The member 50 is provided with a threaded extension 69 on which an adjusting cap 70 is threadably secured. The cap 70 is provided with a pusher bar 71 that bears against the base of the bellows 67. As in the embodiment illustrated

in Figure 1 it is necessary to prefill the fluid chamber 62, passage 60 and chamber 65. The cap 70 must be adjusted until the bellows 67 exerts enough pressure on the fluid in chamber 65 to produce the desired pressure on the bellows 52 and stem 54 to in turn position the valve face 56 against its valve seat 57 producing a closed position at a predetermined ambient temperature. The cap 70 when turned to its minimum temperature setting should open valve 55 to thus allow the escape of air from the radiator as in normal operation. The functioning of the structure is similar to the embodiment illustrated in Figure 1, that is when the valve 40 is secured to a radiator by means of its threaded end 41, it is ready to control the escape of air from that radiator. As normally is the case the air will pass the valve 55 and escape out a plurality of apertures 34. When steam or vapor contacts the chamber 62 the rise in temperature will cause the fluid therein to expand and thus exert a fluid pressure through passage 60 on the fluid in chamber 65 and in turn on the bellows 52 to move the valve stem 54 and in turn close the valve face against its valve seat 57, closing the escape of steam or vapor from the valve. Similarly when the valve is open any temperature rise surrounding the fluid chamber 65 will produce an expansion of the fluid therein and cause the valve to be closed, thus cutting off the normal escape of air from the radiator and thus preventing it from becoming heated by the steam. In effect the radiator is air locked until the ambient temperature drops and allows the valve to be opened again. It is apparent that cap 70 may be turned according to Figures 2 and 3 until a new temperature setting is obtained, thus the valve will function as described above except that it will close when the ambient temperature is the same as the new temperature setting.

Referring to Figure 4, there is still a further embodiment illustrated, utilizing a valve similar to that shown in Figure 1 but in addition the member 20 is provided with an outlet 75 that is connected to a tube 76. The tube 76 is in turn connected to a remote temperature responsive element 80 and specifically to a fluid port 81. The element 80 is comprised of a fluid filled tubular element that forms a chamber 82, the chamber 82 being filled with the same fluid that fills the member 20 and therefore fills the tube 76 that is open to both chambers. The element 80 is provided with a diaphragm 83 having a bellows 84 mounted thereon to close one end 85 of the tubular element 80. The end 85 is provided with an external thread 86 so that an adjusting cap 87 may be threadably secured. The cap 87 is provided with a pusher bar 88 that extends inwardly to bear against a base 89 of the bellows 84. The cap 87 is threadably secured to element 80 and adjusted to a predetermined calibrated position so that the valve 29 as shown in Fig. 1 will be closed by the fluid pressure when the ambient temperature about the element 80 is above the calibrated setting of the cap 87. The cap 87 is calibrated similar to the cap 70 illustrated in Figure 2 and functions in a similar manner. Therefore any desired setting of cap 87 between a minimum and maximum temperature setting will in turn open or close the valve 29 according to the fluid pressure on the bellows 23; this in turn controls the flow of air or steam that may be held in check by the valve when connected to a steam radiator. In view of the temperature setting cap member 87 it is appar-

ent that the valve unit 10 when connected as shown in Figure 4, does not require the scale 31 and threadably secured mounting of member 20. Member 20 should be set with relation to member 15 so that all adjustments are controlled by cap 87.

Various changes and modifications may be made to this device without departing from the spirit of this invention and this invention shall be limited only by the appended claims.

What is claimed is:

1. A thermostatically controlled radiator air release valve comprising a casing that forms a seat for a single valve to control the escape of air, a thermostatic unit threadably secured to said casing, said unit expanding or contracting with the rise or drop in temperature in the surrounding air, said unit supporting the valve adjacent to its seat to open or close according to the prevailing temperature, said thermostatic unit connected to a temperature responsive element located within said casing and on the opposite side of said valve to said unit, said temperature responsive element responding to the temperature of the fluid issuing from the radiator, said thermostatic unit expanding or contracting with the rise or drop in temperature of the fluid issuing from the radiator to in turn open or close said valve.

2. A thermostatic air release valve for steam radiators that is controlled by surrounding room temperature comprising a casing enclosing a single valve and a thermostatic element, said thermostatic element divided into a pair of fluid chambers with a hollow tube connecting both chambers, a fluid filling each chamber and said tube, said hollow tube supporting said single valve, said casing provided with a valve seat adjacent to and mating with said valve means to effect the movement of said normally open valve to a closed position with a predetermined rise in temperature around the one chamber that is affected by room temperature, and means to effect a rapid movement of said valve to a closed position with a sudden rise of the temperature around said other chamber that is affected by the fluid temperature.

3. In a device according to claim 1, which includes a separate valve seat fitted into said casing to provide a tight seal but allow a reciprocating movement, a spring mounted in said casing under said valve seat to protect said valve from excessive pressure when there is an unusual rise in the prevailing temperature.

4. A thermostatic air release valve for steam radiators that is controlled by surrounding room temperature and is also effected by the temperature of the fluid issuing from the radiator comprising a casing that forms a seat for a single valve to control the escape of air from said radiator, a thermostatic unit threadably secured to said casing and supporting the valve element adjacent to its seat to open or close according to the prevailing temperature, said

thermostatic unit divided into a first and second fluid chamber with a hollow tube connecting both chambers, a fluid filling each chamber and said tube, said first fluid chamber located outside of said casing on one side of said valve, and said second fluid chamber located inside said casing on the opposite side of said valve, said hollow tube passing through said valve, said first fluid chamber responding to the temperature of the air surrounding said casing and thermostatic unit to expand or contract said thermostatic unit and in turn open or close said valve, said second fluid chamber responding to the temperature of the fluid issuing from the radiator to expand or contract said thermostatic unit and in turn open or close said valve.

5. In a device according to claim 4, said casing being cylindrical with an inlet port at one end and said valve seat at the opposite end and in which said thermostatic unit that is affected by room temperature is mounted to said casing opposite to the inlet port, to prevent the exposure of said thermostatic unit to the steam entering said valve.

10. 6. In a device according to claim 1, said thermostatic unit comprised of a diaphragm and second casing to enclose a fluid, a calibrated pressure element threadably secured to said second casing and bearing against said diaphragm, means to change the degree of opening of said valve to change the temperature setting at which the valve will open or close.

15. 7. In a device according to claim 1, said thermostatic unit comprised of a diaphragm and second casing to enclose a fluid, a calibrated pressure element threadably secured to said second casing and bearing against said diaphragm, means to increase or decrease the orifice opening of said valve in direct relation with the drop or rise in ambient temperature around said casing.

20. 8. In a device according to claim 4, said first fluid chamber comprised of a diaphragm and second casing, a calibrated pressure element threadably secured to said thermostatic unit and bearing against said diaphragm, means to change the degree of pressure on said diaphragm to change the temperature setting at which the valve will open or close.

25. 9. In a device according to claim 4, said first fluid chamber comprised of a diaphragm and second casing, a calibrated pressure element threadably secured to said thermostatic unit and bearing against said diaphragm, means to change the degree of pressure on said diaphragm to change the temperature setting at which the valve will open or close.

30. 10. In a device according to claim 4, said first fluid chamber comprised of a diaphragm and second casing, a calibrated pressure element threadably secured to said thermostatic unit and bearing against said diaphragm, means to change the degree of pressure on said diaphragm to change the temperature setting at which the valve will open or close.

35. 11. In a device according to claim 4, said first fluid chamber comprised of a diaphragm and second casing, a calibrated pressure element threadably secured to said thermostatic unit and bearing against said diaphragm, means to change the degree of pressure on said diaphragm to change the temperature setting at which the valve will open or close.

40. 12. In a device according to claim 4, said first fluid chamber comprised of a diaphragm and second casing, a calibrated pressure element threadably secured to said thermostatic unit and bearing against said diaphragm, means to change the degree of pressure on said diaphragm to change the temperature setting at which the valve will open or close.

45. 13. In a device according to claim 4, said first fluid chamber comprised of a diaphragm and second casing, a calibrated pressure element threadably secured to said thermostatic unit and bearing against said diaphragm, means to change the degree of pressure on said diaphragm to change the temperature setting at which the valve will open or close.
